UNITED STATES PATENT OFFICE.

JOHN RANDOLPH SEES, OF NEW YORK, N. Y., ASSIGNOR TO WILLIAM F. WEAVER, OF PHILADELPHIA, PENNSYLVANIA.

IMPROVEMENT IN CHECK-VALVES.

Specification forming part of Letters Patent No. 42,541, dated April 26, 1864.

To all whom it may concern:

Be it known that I, JOHN RANDOLPH SEES, of the city of New York, in the State of New York, have invented a certain new, useful, and Improved Valve for Feed-Water Pipes, &c.; and I do hereby declare the following to be a full, clear, and exact description thereof, reference being had to the accompanying drawings, and to the letters and marks thereon.

Figure 1 of the drawings forming part of this specification is a side view of the rear end of a locomotive-boiler, the heating feed-water pipes being within the smoke-box *a*, the lower end thereof being in communication with the check-valve chamber *b*, through which the feed-water passes by a pipe, *c*, and the upper end thereof being in communication with the water space of the boiler by a pipe, *d*. The point of attachment of the pipe from the feed pump is marked *e*.

A check-valve is shown within the valve-chamber *b*, also shown detached by Fig. 2, and within the chamber *b* by Fig. 3.

A circulating-pipe, *f*, passes out of the top of the valve chamber to the water-space of the boiler, for the purpose of keeping up a circulation of water through the heating pipes when the supply of water to them from the feed pump is shut off. As shown in Figs. 1 and 3, the valve rests on its lower seat, indicating the circulation of water through the pipe *f*. When the water is passing through the chamber by the action of the feed-pump, the valve will be against its upper seat. This upper seat, *x*, as is shown by Fig. 3, is so made that it can be removed. It is turned to fit the shell of the valve-seat, and admits of being removed at pleasure for the purpose of turning off the ends or packing under it for the purpose of altering the lift of the valve. The grinding down of the valve has been the usual means of altering the lift, but by this improvement the upper seat alone is altered, which can be done in a few moments, and thus the necessity of touching the valve obviated.

My improvement relates to the valve and the removable seat, which, though specially designed for heating feed-water pipes or the

valve-chamber thereof, may be used in other pipes or pieces of apparatus and for other purposes.

The valve *g* is cylindrical, with recessed ends *h* and *i*, and with a groove or depression, *j*, around the central portion of it. Studs or projections *k* at each end of the valve or ribs *o* in the chamber guide it and keep the space perfect between it and the sides of the valve-chamber. The valve may be made of any material and in any manner applicable to valves generally. The advantages of this valve are, that while the groove *j* gives an increased surface for the water, it also performs a special function. Should the water have a tendency to come back from the heater on entering the valve-chamber, it would strike the groove and lift the valve on the upper seat for a moment, and check its further passage until the column of water was again complete, and then would resume its circulation. The only time it has a tendency to do so is when getting up steam and the heater is much hotter than the boiler, but as soon as vapor forms in the boiler this will not happen. The recessed ends *h* and *i* serve as cushioning-surfaces, the air of the water and the water between the ends of the valve and its seats being the cushioning materials.

As a check-valve, this valve will not be as liable to breakage from the action of the pump as many other valves, while it will work smooth and be free from slamming.

What I claim as my invention, and desire to secure by Letters Patent, is—

1. The valve *g*, with recessed ends *h* and *i* and with a groove or depression, *j*, and susceptible of being operated substantially as herein set forth.

2. In combination with a check-valve constructed as herein described, the removable seat, for the purposes herein recited.

This specification signed this 30th day of September, 1863.

JOHN RANDOLPH SEES.
